COMBINED SEPARATOR AND HEAT EXCHANGER

George A. Worn, Montclair, N. J., assignor to The Lummus Company, New York, N. Y.

Application April 27, 1933, Serial No. 668,144

2 Claims. (CL 257—223)

My invention relates to the art of heat exchange and has as its principal object the provision of an arrangement requiring a minimum ground space but having high heat efficiency and being convenient to a high degree.

It is a common practice in the petroleum refining trade to discharge the highly heated fluid from a tube type heating coil into a tall separating and/or vaporizing chamber and to conduct the vapors from such chamber to a heat exchanger in which the heat of the vapors is transmitted to a considerable extent to raw oil moving toward the heating coil. In apparatus within my invention, the separating and/or vaporizing chamber may be combined with the heat exchange elements in such manner that only one foundation is required and no additional ground space need be used over that above the separating chamber itself. Also, the heat exchange elements may be readily inspected and cleaned when required.

In order that my invention, together with its objects and advantages may be readily and fully understood, I will now describe by way of example and in connection with the accompanying drawings a combined separating and/or vaporizing chamber and heat exchanger in accordance with my invention and selected from a number of possible embodiments thereof. In the drawings,

Fig. 1 is an elevation, parts being broken away, of an apparatus within my invention.

Fig. 2 is a plan view of a header ring appearing in Fig. 1.

Fig. 3 is a transverse section through the center of the ring shown in Fig. 2.

In the installation illustrated in Fig. 1, the separating and vaporizing chamber 10 has inlet 12 in its lower end which connects with the discharge of a heating or cracking still of the coil or other type. Mingled vapors and/or liquids of high temperature enter the chamber 10 from the coil. Within chamber 10 the pressure is somewhat reduced and the vapors rise to the top of the chamber while the liquids are taken off through outlet 14 and/or through the bottom drain 16.

In the arrangement illustrated, the envelope of the chamber 10 is extended upward in the form of a ring 10a and a casing 10b within which are mounted a plurality of serpentine tubular liquid conducting units 18, 18, such units being supported from the said ring. Preferably, there are two detachable joints in the envelope of chamber 10, one joint 20 being at the lower

edge of ring 10a and the other joint 22 between ring 10a and casing 10b.

Ring 10a is shown as an integral casting within which are two integral manifold chambers 24 and 26 each of which is closed at one end while the other end extends to the outside of the ring where it can be connected to an inlet or outlet pipe by a flange or other type coupling 28. The top walls of chambers 24 and 26 are drilled and countersunk to provide passages 30, 30 and seats 10 32, 32 whereby the ends of the units 18 may be coupled by readily breakable joints to the walls of the chambers 24 and 26 in position to receive fluid from or discharge fluid to such chambers. Each unit 18 is formed of a zigzag tube and all 15 the units together form a bundle through which a cooling fluid flows.

Vapors from the lower part and main part of chamber 10 pass up around the units 18 to heat the liquid therein. For this purpose I have made ring 10a with a wide aperture therethrough between manifold chambers 24 and 26. However, any form of vapor connection between the lower portions of chambers 10 and the portion within casing 10b may be employed within my invention. In the arrangement illustrated, a horizontal baffle 34 is placed below a portion of the opening 33 through ring 10a and the gases pass up through the other half of such opening into the tube bundle formed of units 18. A vertical 30 baffle 36 extends from the bottom of the tube bundle part way up the middle of such bundle so that the vapors pass around the upper edge of baffle 36 and then downwardly through the other half of the tube bundle and out through opening 38 in the ring 10a. However, I do not limit myself to any particular form of path for the vapors through the space occupied by the units 18 and one may use a single or a multiple path arrangement within my invention as desired. 40 Condensate formed within the casing 10b at the left of the central baffle 36 drains back through the opening in the ring 10a into chamber 10. Such condensate as is formed within the casing 10b at the right of central baffle 36 may be 45 trapped back into the chamber 10 by suitable means not shown, but preferably is permitted to flow out with the gases through the outlet 38 so that it can be trapped out of the line connected to such outlet at any convenient place.

It will be understood that chamber 10 may in practice often be eighty or so feet high and I have shown means at the top of such chamber for lifting the casing 10b clear of the units 18 to permit inspection and cleaning of the units. Such means 55

comprises a framework 38 fixed to the upper portion of the chamber and extending above the casing 10b. On the framework 38 is a trolley device 40 so that, when joint 22 has been broken, the casing 10b can be hoisted by tackle means (not shown) and attached to trolley 40 and held out of the way above the units 18. By such arrangement the ground space of a plant in which my invention may be used is economized to the maximum degree. However, I do not limit myself to this in all cases.

It will be understood further that I do not limit myself in all cases to details of the foregoing description, but wish the following claims to be construed as broadly as their terms and the state of the art permits.

What I claim is:

1. The combination in a heat exchanger of a base ring having a wide central opening and a side opening, a casing on said ring, a tube bundle supported from said ring and extending into said casing, connections whereby one fluid may pass through said bundle and baffling means whereby another fluid passing through the central aperture in said ring may pass over said bundle and out through said side opening.

2. The combination as set forth in claim 1 and in which the ring has header chambers therein on opposite sides of its central opening.

GEORGE A. WORN. 15
